UNITED STATES PATENT OFFICE.

CONRAD HUBERT, OF NEW YORK, N. Y.

PORTABLE ELECTRIC LIGHT.

No. 818,449.

Specification of Letters Patent.

Patented April 24, 1906.

Application filed May 19, 1905. Serial No. 261,156.

To all whom it may concern:

Be it known that I, CONRAD HUBERT, a citizen of the United States, residing in the borough of Manhattan, city of New York, in the county of New York and State of New York, have invented certain new and useful Improvements in Portable Electric Lights, of which the following is a specification, reference being had therein to the accompanying drawings, forming a part thereof.

My invention relates to portable electric lights, and particularly those of small dimensions and convenient shape to adapt them to be carried in the pocket of the user.

My invention has for its objects simplicity and compactness of construction, non-liability to accidental closure of circuit and consequent exhaustion of battery, durability, ease and reliability of operation, and ready change from a condition wherein light is obtainable only so long as the circuit-closing device is held closed by the operator to a condition in which the circuit will be maintained in closed condition and the light maintained without effort on the part of the operator.

In portable electric lights of this class the amount of battery-power which can be obtained in an appliance of such small dimensions is necessarily not great, and accidental or unnecessary closures would too speedily exhaust the battery. It is therefore desirable that all circuit-closing means should be effectually shielded. It is also desirable that the operation of closing the circuit and thereby obtaining the light should be readily and easily performed and that when the light is desired for momentary or short periods the circuit-closer should automatically open the circuit and that when the light is desired for longer periods the circuit may be kept closed without effort on the part of the user.

The improved means embodying my invention enable the user to force the circuit-closer into closed-circuit condition by co-operation of a push-button and a fixed abutment on the casing. Means are provided whereby the push-button is normally held in a position such that it is operative in the usual manner and permits the circuit-closer to automatically return from closed-circuit to open-circuit condition, but may also be forcibly moved from this normal position to force the circuit-closer into closed-circuit condition by wedging between it and the fixed abutment.

My invention also includes improvements

in the construction and attachment of the lamp socket and lens.

I will now describe the portable electric light illustrated in the accompanying drawings and embodying my invention and will thereafter point out my invention in claims.

Figure 1 is a front elevation of the portable light, partly in section. Fig. 2 is a side elevation looking toward the narrow side of the device with the circuit-closer adjusted for momentary closure and automatic opening. Fig. 3 is a similar view, partly in section, with the circuit-closer locked in closed position. Fig. 4 is an underneath plan view of the upper cover of the device detached to show the fitting of the lamp-socket in the upper cover. Fig. 5 is a sectional view of the device, taken in a plane indicated by the line 5 5 in Fig. 1, the battery not being shown in section. Fig. 6 is an enlarged sectional view of the contact device in its open-circuit position and automatically-opening condition. Fig. 7 is an enlarged sectional view of the contact device in its locked closed-circuit position.

The casing *a* is shaped to form a thin flat package without angular corners or protuberances, so as to be well adapted to be carried in the pocket of the user. The body of the casing is made of metal or conductive material, and the casing is wide at the flat sides and semi-cylindrical at the thin sides, so as to follow closely the contour of the inclosed battery-cells. The end pieces or covers are made of metal or conductive material and fit over the adjacent ends of the casing, the upper cover *b* being slidably removable, while the lower cover *c* is not designed to be removable. The remaining uncovered portion of the casing is wrapped about with a suitable covering *d*.

The lighting element is sunk completely within the casing and consists of a miniature incandescent electric lamp *e*, which is threaded into a metallic socket *k* and which carries at its lower end a yielding contact device consisting of a helical spring *l*. This lamp-socket *k* is shaped like an inverted dome and is fitted to the upper cover *b* by means of lateral projections shown as formed by a flange *m* of generally circular outline with diametrically opposite portions flattened so as to be of smaller diameter, so that the portions of smaller diameter freely enter the cover and upon turning the lamp-socket through about a quarter of a turn the circular portions of the flange enter counterpart recesses *n* and firmly lock the lamp-socket in position. The

inner wall of the socket is provided with a reflecting-surface, and as a result of its concave shape produces in common with the directing action of the lens *o* a powerful and effective light. This lens is fixedly set in the casing, being seated in a rim on the outer face of the cover and held against the rim by the flange of the combined light-reflector and lamp-socket *k*, which bears tightly against the base of the lens. Access may be had to the lens and the lamp also for removal or replacement by removing the upper cover *b* from the casing and then removing the lamp-socket *k* from the upper cover.

Upon the inner face of one of the thin sides of the casing *a* two rounded spacing projections *p* are provided. These bear against the adjacent side of the battery-package and not only prevent any free movement of the battery-package and the consequent short-circuiting of the uncovered portions of the latter with the casing, but also assure a space between the battery-package and the casing for the movement of the contact-spring *q* against the zinc terminal of the battery-cell.

A circuit-closer is provided adapted for manual operation and located at one of the sides of the casing, so that it is in convenient position to be operated by the thumb or one of the fingers of the user. The circuit-closer is resilient and is normally in circuit-opening position. It comprises a push-button *r* and a spring contact-finger *g*, the contact-finger being shown as secured at its lower end by a rivet *j* to the inner face of the thin side of the casing *a* and the push-button being externally located within a shield *s*, this shield being shown as of nearly elliptical form and mounted upon the outer surface of the casing and secured thereto by two side flaps *t*. This shield so surrounds and protects the push-button as to obviate the liability of accidental closing of the circuit when the device is carried in the pocket of the user. The push-button *r* is shown as made up of a circular head *r'*, a circular base *r''*, with two intermediate portions *u* and *v*, the front intermediate portion *u* being of smaller diameter than the head and the rear intermediate portion *v* being of larger diameter than the portion *u*, so that an annular groove is formed at *u*, and the rear intermediate portion *v* being of smaller diameter than the base *r''*, so that it moves freely through the upper circular part of an opening *x* in the shield, while the base forms a shoulder of larger diameter than the orifice *x*, effectually preventing removal exteriorly of the push-button.

The push-button is not fastened to the contact-finger; but these parts are provided with an engaging projection and depression which tend to hold the push-button in a predetermined position relatively to the contact-spring, such position being that in which the push-button is retained in and automatically

returned to open-circuit condition. As shown, a rounded projection *w* is formed at the rear face of the base of the push-button and the contact-spring has a registering perforation to receive this projection, this construction being exceedingly simple and reliable.

To provide for maintaining a closed-circuit condition, the opening *x* in the shield has, in addition to the circular upper part above mentioned, an elongated lower part or slot of such width as to receive the annular groove *u* of the push-button, so that the push-button may be pressed slightly inward from the normal position (shown in Fig. 6) to register the groove *u* with the outer wall of the shield and may then be pressed downward in the slot of the shield with the groove *u* engaged by the walls of the shield, the rear projection *w* of the bush-button riding out of the perforation of the contact-spring and the push-button bearing against the contact-spring and forcing it inward as the push-button is moved downward until the contact-spring bears against the conductive wall of the adjacent battery-cell, this being its circuit-closing position. With the parts in this position the resilience of the contact-spring causes an outward pressure on the push-button, which develops sufficient friction to hold the parts in this position, and the parts are, in fact, locked in closed-circuit condition. This locked closed-circuit condition is shown in Figs. 3 and 7. It will be maintained until the push-button is moved upward by the operator. As the push-button attains its normal position relatively to the contact-spring the rounded rear projection *w* will enter the perforation in the contact-spring and the contact-spring will force the push-button outward and all parts will attain the normal open-circuit position (shown in Figs. 2 and 6,) the groove *u* being held out of register with the slot in the shield. For ordinary push-button use it is only necessary to press the push-button in and hold it in so long as the light is required. The engagement of the push-button and contact-spring prevents shifting of the parts from normal positions, this being also aided by normal alignment of the larger intermediate part *v* of the push-button with the wall of the socket, which prevents jarring of the push-button downward into the slot and prevents movement of the push-button into the slot by any other movements than the initial inward movement and following downward movement above described.

The battery is composed of a plurality of cells arranged side by side and fitting within the casing. The construction and arrangement is such as is covered in my Patent No. 762,720, dated June 14, 1904, the battery substantially filling the casing and the cells being insulated from one another. For convenience of manufacture and sale of the bat-

terry a wrapping of insulating material is provided over all of the cells, which holds them together in one package or unit. When the battery is exhausted, it may be removed from the casing and replaced by a new one.

The electric conductive means for the circuit of the battery and lamp are partly provided by the casing and include the normally open circuit-closer, comprising the push-button *r* and contact-spring *q* previously described. The lamp *e* has one of its terminals *l* in direct contact with the carbon terminal of the middle cell *g* of the battery. The several cells of the battery are connected in series in usual manner, the carbon terminal of the middle cell *g* and the zinc casing of the right-hand outer cell *f* being the end terminals of the battery. The zinc casing of the cell *f* is included in the lamp-circuit by direct contact of the spring or circuit-closer *q* with the conductive casing *a*, the insulated wrapping being removed in proximity to the point of contact. The current passes to the cover *b*, flows through the combined reflector and lamp-socket *k*, and enters the lamp *e*.

It is obvious that various modifications may be made in the construction shown and above particularly described within the principle and scope of my invention.

What I claim, and desire to secure by Letters Patent, is—

1. A portable electric light comprising a casing and a battery therein, an electric lamp carried by the casing, and circuit-completing means from the battery to the lamp including a push-button and a contact, the casing having a fixed abutment for the push-button and the push-button being movable from a position in which the contact is actuatable by the push-button to close the circuit and is permitted to automatically return from circuit-closing to circuit-opening condition, to a position in which the push-button is coöperative with the fixed abutment to force the contact into circuit-closing condition.

2. A portable electric light comprising a casing and a battery therein, an electric lamp carried by the casing, and circuit-completing means from the battery to the lamp including a push-button and a contact-finger, the contact-finger being within the casing and arranged to abut against a battery-terminal, the casing having an abutment for the push-button and the push-button being movable from a position in which the contact-finger is actuatable by the push-button to close the circuit and is permitted to automatically return from circuit-closing to circuit-opening condition, to a position in which the push-button is coöperative with the abutment to force the contact-finger into circuit-closing condition.

3. A portable electric light comprising a casing and a battery therein, an electric lamp

carried by the casing, and circuit-completing means from the battery to the lamp including a push-button and a contact-finger, the push-button and the contact-finger having an engaging projection and depression to normally hold the push-button in a position in which the contact-finger is actuatable by the push-button to close the circuit and is permitted to automatically return from circuit-closing to circuit-opening position, and the push-button and casing having a sliding connection whereby the push-button may be moved relatively to the contact-finger to abut against the casing and force the contact-finger into circuit-closing position.

4. The combination of a casing and a battery therein, and means for closing the circuit of the battery, including a push-button and a contact-finger, the casing being provided with an opening in part large enough to permit the push-button to be moved inward to thrust the contact-finger into circuit-closing position with freedom to automatically return from such circuit-closing position and the opening in the casing being in part adapted to engage the push-button and permit the push-button to be moved to wedge the contact-finger into circuit-closing position.

5. The combination of a casing and a battery therein, and circuit-completing means for the battery including a push-button and a contact-finger, the push-button having a peripheral groove and the casing being provided with an opening in part large enough to permit the push-button to be moved inward to thrust the contact-finger into circuit-closing position with freedom to automatically return from such circuit-closing position, and the opening in the casing being in part narrower to engage the peripheral groove of the push-button and permit the push-button to be moved to wedge the contact-finger into circuit-closing position.

6. The combination of a casing and a battery therein, and circuit-completing means for the battery including a push-button and a contact-finger, the push-button and the contact-finger having an engaging projection and depression and the push-button having a peripheral groove therein, the casing being provided with an opening in part large enough to permit the push-button to be moved inward to thrust the contact-finger into circuit-closing position with freedom to automatically return from such circuit-closing position, the engaging projection and depression being located so as to normally hold the push-button in such position of automatic return, and the opening in the casing being in part narrower to engage the peripheral groove of the push-button and permit the push-button to be moved to wedge the contact-finger into circuit-closing position.

7. The combination of a casing, a shield

thereon, a battery carried by the casing, and means for closing the circuit of the battery including a push-button and a contact-finger, the shield being provided with an opening in 5 part large enough to permit the push-button to be moved inward to thrust the contact-finger to the circuit-closing position with freedom to automatically return from such circuit-closing position and the opening in 10 the shield being in part adapted to engage the push-button and permit the push-button to wedge the contact-finger into circuit-closing position.

8. The combination of a casing, a shield 15 thereon, a battery carried by the casing, and means for closing the circuit of the battery including a push-button and a contact-finger, the push-button and contact-finger having an engaging projection and depression and 20 the shield having an opening therein in part large enough to permit the push-button to be moved inward to thrust the contact-finger into circuit-closing position with freedom to automatically return from such circuit-closing 25 position, the engaging projection and depression normally holding the push-button in such position of automatic return, and the opening in the shield being in part adapted to engage the push-button and permit the 30 push-button to be moved to wedge the contact-finger into circuit-closing position.

9. The combination of a casing, a shield thereon, a battery carried by the casing, and means for closing the circuit of the battery 35 including a push-button and a contact-finger, the contact-finger being arranged so as to close the circuit by contact with the battery,

spacing projections extending inward from the wall of the casing above and below the contact-finger, the push-button and contact-finger being engageable to normally hold the push-button in a position in which the contact-finger is permitted to automatically return from circuit-closing to circuit-opening position and the push-button being movable 45 relatively to the contact-finger to lock the contact-finger in circuit-closing condition.

10. A portable electric light comprising a casing and a battery therein, a cover for the casing having recesses therein, an electric 50 lamp, a lamp-socket having opposite lateral projections adapted to be engaged in the recesses of the cover by part rotative movement of the lamp-socket relatively to the cover, and means for completing and closing 55 the circuit from the battery to the lamp.

11. A portable electric light comprising a casing and a battery therein, a cover for the casing having recessed portions therein, an electric lamp, a lamp-socket having opposite 60 lateral projections adapted to be engaged in the recesses of the cover by part rotative movement of the lamp-socket relatively to the cover, a lens fitted in the cover and held in place by the lamp-socket, and means for 65 completing and closing the circuit from the battery to the lamp.

In testimony whereof I have affixed my signature in presence of two witnesses.

CONRAD HUBERT.
